UNITED STATES PATENT OFFICE.

VICTOR BIART, OF STUTTGART, GERMANY.

COVER FOR FRUIT-JARS.

SPECIFICATION forming part of Letters Patent No. 531,253, dated December 18, 1894.

Application filed April 19, 1894. Serial No. 507,415. (No model.)

To all whom it may concern:

Be it known that I, VICTOR BIART, captain United States Army, retired, residing at Stuttgart, Germany, have invented a new and useful Improved Cover for Fruit-Jars, of which the following is a specification.

My invention relates to improvements in fruit jars.

The object of my invention is to provide a jar specially adapted for preserving fruits or vegetables.

In the usual method of preserving fruits and the like, the articles to be preserved are placed in the jars and heat then applied to expel the air from the jar. In some cases, the lid is applied to the jar and held down by a spring which yields when the internal pressure is sufficient to overcome its resistance.

My invention consists in a jar especially constructed for use in the manner last set forth, and particularly in a device for determining the proper pressure to be applied to the spring.

My invention further consists in a rubber packing ring of novel construction.

My invention also consists in the features, details and combinations of parts which will first be described in connection with the accompanying drawings and then particularly pointed out in the claims.

In the drawings—Figure 1 is a vertical section, partly in elevation, of a jar embodying my invention; Fig. 2, a side elevation; Fig. 3, a top plan view, and Fig. 4 a transverse section through the clamp, c, and screw, d.

Referring to the drawings, A is a jar provided with a lip or flange, a, at its mouth and having its upper edge ground flat. On the top edge of the jar is placed a horizontal annular ring, g, of flexible material, preferably india-rubber. This ring, which may be termed the "packing ring," is provided with a vertical annular projection, g', rising from the inner periphery of the horizontal portion, g. Upon the portion, g, of the packing ring is placed a cover, B, provided with an annular downward-extending flange, b', whose lower face is ground, for a purpose hereinafter described. The interior diameter of the cover is equal to the exterior diameter of the vertical annular projection, g', on the packing

ring. The top of the cover is provided with projections or lugs, b, which may be termed "gage-lugs," the purpose of which will be explained hereinafter.

55

Upon the top of the cover is placed a bow-shaped spring, D, whose ends rest on the cover, and whose central portion is engaged on the upper surface by the lower end of a thumb screw, d, threaded through a yoke, C, which is provided at its lower ends with ears, c, which are adapted to engage the under surface of the lip or flange, a, on the jar, A.

In using my apparatus, the jar, when filled with the articles to be preserved, is covered 65 by putting on the packing ring, g, and cover, B, after which the spring, D, and yoke, C, are put in place and the thumb-screw, d, turned to force the central portion of the spring, D, down until the lower edge of the said spring 70 is just level with the upper edge of the lugs, b. If, now, the jar be exposed to heat in any suitable manner, the internal pressure of the air and steam will force the cover, B, upward and thus permit the confined air to escape. 75 When all the air has been driven out of the jar, the latter is then permitted to cool, the atmospheric pressure being then sufficient to hold the lid in place without the aid of the yoke and spring, which may then be removed 80 and applied to another jar.

It is to be observed that the top edge of the jar and the lower edge of the cover or lid are both without indentations, so that they can each be ground on the edges without inconvenience whereby a better joint is made between the jar, packing ring and cover.

The object of providing the packing ring with a vertical annular projection is to prevent the internal pressure from blowing out 90 the said packing ring, and it is obvious that, instead of the said vertical annular projection, a series of vertical lugs may be employed.

The lugs, b, on the cover, B, are so proportioned with relation to the strength of the 95 spring, D, that when the said spring is compressed to the level of the top of the lugs, the pressure exerted to hold the cover on the jar will be such as is proper to allow the escape of air and prevent bursting of the vessel.

I am aware that jars provided with spring-held covers are old, but so far as I have any

knowledge, none of such jars have projections on the lid for the purpose of indicating the proper amount of tension on the spring.

Having thus fully described my invention, 5 what I claim as new, and desire to secure by Letters Patent, is—

1. The combination, with a fruit jar, of a cover provided with upward-projecting gage-lugs arranged with a space between them, a 10 yoke arranged to engage the fruit jar, a screw passing through the yoke, and a spring located over the space between the lugs and having its ends resting on the cover, its central portion coinciding with the screw, substantially as set forth.
2. The combination, with a fruit-jar having a flange around its mouth, a yoke engaging the flange, a screw passing through the yoke, and a spring beneath the lower end of the 15 screw, of a cover provided with an upward-projecting lug arranged at one side of the spring, substantially as set forth.
3. The combination, with a fruit-jar having a flange around its mouth, of a cover provided 20 with upward-projecting lugs arranged with a space between them, a yoke engaging the flange, a screw passing through the yoke, and a spring located over the space between the lugs and having its ends resting on the cover, 25 its central portion contacting with the screw, substantially as set forth.
4. A packing ring for fruit-jars comprising an annular portion and a vertical projecting portion rising from the inner periphery of the 30 annular portion, substantially as set forth.
5. A packing ring for fruit jars comprising an annular horizontal portion and an annular vertical portion connected to the horizontal annular portion at the inner periphery of 35 the latter, substantially as set forth.
6. The combination, with a fruit-jar, a cover having an annular downward-extending flange, and means for holding the cover onto the jar, of a packing ring having a horizontal annular portion interposed between 40 the lower surface of the flange on the cover 45

and the upper surface of the jar, and a vertical portion extending upward inside the flange on the cover and contacting therewith, substantially as set forth. 50

7. The combination, with a fruit-jar, a cover having an annular downward-extending flange, and means for holding the cover onto the jar, of a packing ring having a horizontal annular portion interposed between 55 the lower surface of the flange on the cover and the upper surface of the jar, and an annular vertical portion extending upward inside the flange on the cover, and contacting therewith, substantially as set forth. 60

8. The combination, with a fruit-jar having a flange around its mouth, a cover having an annular downward-extending flange, a yoke engaging the flange on the jar, and means intermediate the yoke and cover for holding 65 the latter onto the jar, of a packing ring having a horizontal annular portion interposed between the lower surface of the flange on the cover and the upper surface of the jar, and a vertical portion extending upward inside the 70 flange on the cover and contacting therewith, substantially as set forth.

9. The combination, with a fruit jar having a flange around its mouth, a cover having an annular downward-extending flange, a yoke 75 engaging the flange on the jar, and means intermediate the yoke and cover for holding the latter onto the jar, of a packing ring having a horizontal annular portion interposed between 80 the lower surface of the flange on the cover and the upper surface of the jar, and an annular vertical portion extending upward inside the flange on the cover and contacting therewith, substantially as set forth.

In testimony whereof I have signed this 85 specification in the presence of two subscribing witnesses.

VICTOR BIART.
